UNITED STATES PATENT OFFICE.

ORIN C. FENLASON, OF RAYMOND, WASHINGTON.

COLLAPSIBLE VENEER BOX.

1,152,084.

Specification of Letters Patent. Patented Aug. 31, 1915.

Application filed July 10, 1913, Serial No. 778,414. Renewed July 22, 1915. Serial No. 41,390.

To all whom it may concern:

Be it known that I, ORIN C. FENLASON, a citizen of the United States, residing at Raymond, in the county of Pacific and State of Washington, have invented a new and useful Collapsible Veneer Box, of which the following is a specification.

The invention relates to improvements in collapsible veneer boxes for berries, fruit, 10 vegetables, etc.

The object of the present invention is to improve the construction of collapsible veneer boxes for berries, fruit, vegetables, etc., and to provide a simple, strong, practical 15 and easily constructed veneer box, adapted to be shipped in a knockdown condition to effect a saving in both space and freight, and capable of being easily and quickly arranged for use.

With these and other objects in view, the invention consists in the construction and 20 novel combination of parts hereinafter fully described, illustrated in the accompanying drawings, and pointed out in the claims 25 hereto appended; it being understood that various changes in the form, proportion, size and minor details of construction, within the scope of the claims, may be resorted to without departing from the spirit or sacrificing any of the advantages of the invention.

In the drawings:—Figure 1 is a perspective view of a collapsible veneer box, constructed in accordance with the present invention. Fig. 2 is a central vertical sectional view of the same. Fig. 3 is a detail perspective view of one of the bottom members. Fig. 4 is a similar view of the body strip. Fig. 5 is a detail view, illustrating 35 another form of the invention. Fig. 6 is a detail sectional view, illustrating another means for securing the terminal flaps to the supporting portions of the bottom to form the clamping means for engaging the body 40 of the box.

Like numerals of reference designate corresponding parts in all the figures of the drawings.

In the accompanying drawing in which is 50 illustrated the preferred embodiment of the

invention, 1 designates a rectangular body constructed of a single strip or sheet of veneer of sufficient length to form the sides or walls and to provide overlapped terminal portions 2 and 3. In the form of the invention illustrated in Figs. 1 to 4 inclusive, the overlapped terminals are of the same area as the opposite wall of the body and form a wall of two plies or thicknesses, as clearly shown in Fig. 4 of the drawings. 55 The strip, however, may be only of sufficient length to provide a short overlapped terminal portion 4, which is secured to the adjacent end 5 of the body strip 6 by staples 7, or other suitable fastening means. When 60 the ends of the body strip are not fastened together, the strip may be laid out perfectly flat, and while it is not essential that both of the terminal portions 2 and 3 should be the full length of the two-ply wall, it is preferable 65 to make them so especially when only one of a pair of bottom strips 8 is employed to form the bottom of the box. The strip of veneer is scored at the corners of the box and enables the body either to collapse or to 70 be spread out flat.

The strips 8, which constitute the bottom of the box, are arranged at right angles to each other, and each bottom member consists of a separate strip or sheet of veneer, 75 scored to form a central bottom portion 9, opposite upwardly extending side supporting portions or members 10 and terminal flaps 11, as clearly illustrated in Fig. 3 of the drawings. The terminal flaps 11, which 80 are folded downwardly and outwardly, are secured flat against the outer faces of the supporting portions 10 by a row of stitches 12, extending across each of the terminal flaps 11 and the contiguous supporting portion 10 and arranged adjacent to the upper edge of the latter. The rows of stitches 12 are located above the upper ends of the terminal flaps, which have lower free resilient 85 clamping portions for engaging the opposite side walls of the body of the box. The supporting portions 10 with their stitched flaps 11 are adapted to be either folded inwardly upon the bottom portion 9 or spread 90 out flat.

In assembling the parts of the collapsible veneer box, the body strip is arranged in the form of a rectangle, and the supporting portions of one of the bottom strips are swung 5 upwardly to the position illustrated in Fig. 3 of the drawings. The bottom strip is then introduced into the rectangular body, the supporting portions 10 fitting against the inner faces of the opposite walls, and the 10 stitched terminal flaps engaging the outer faces of such walls, which are frictionally clamped between the supporting portions 10 and the flaps 11, when the bottom member is forced downward into the rectangular body. 15 The other bottom strip is then placed in the body at right angles to the bottom member first introduced therein. The stitched flaps 11 and the supporting portions 10 form clamping means, which firmly hold the bottom 20 strips in engagement with the body strip and securely retain the overlapped ends of the latter in frictional engagement when the same are not fastened by staples.

The supporting portions 10 of the bottom 25 strips project above the upper edges of the body strip and form extensions of the walls thereof and increase the capacity of the receptacle. This enables comparatively narrow strips of veneer to be utilized in the 30 formation of the body of the box, and when two bottom strips are employed, they form a strong and durable box having a two-ply bottom and adapted for handling fruit, vegetables or any similar commodity. Also 35 with the double bottom strip construction, there are no staples exposed at the interior of the box to come in contact with the contents thereof even when the terminals of the body strip are fastened together. When 40 it is desired to construct a cheaper box, one of the crossed bottom strips may be omitted.

The terminal flaps are of less area than the inner supporting portions and they terminate short of the lower edges of the body. 45 Instead of stitching the terminal flaps to the supporting portions of the bottom of the box, various other fastening means may be employed, and in Fig. 6 of the drawing is illustrated a metallic binding strip 13, which 50 not only secures the terminal flaps to the supporting portions but reinforces the said parts and materially increases the durability of the box.

The metallic binding strip 13, which is 55 constructed of thin sheet metal, is bent longitudinally to form inner and outer side flanges 14 between which the supporting portion and the terminal flap are gripped. The binding strip may be simply stamped 60 on the veneer, or it may be positively fastened to the same by any additional means.

What is claimed is:—

1. A collapsible or knockdown veneer box comprising a collapsible body, and a bot-

tom strip of veneer consisting of a bottom 65 portion, upwardly extending side members fitted against the opposite side walls of the body, and terminal flaps folded downwardly and secured flat against the side members and having free resilient lower portions 70 which frictionally engage and clamp the said side walls of the box between them and the side members of the bottom strip.

2. A collapsible or knockdown veneer box comprising a collapsible body, and a bottom 75 strip of veneer consisting of a bottom portion, upwardly extending side members, and terminal flaps folded downwardly and stitched flat against the side members and having free resilient lower portions which 80 frictionally engage and clamp the opposite side walls of the body between them and the side members of the bottom strip substantially throughout the entire length of the said side walls.

3. A collapsible or knockdown veneer box including a body, and a bottom strip of veneer scored at intervals to form a bottom portion, upwardly extending side members, and terminal flaps which are folded downwardly and stitched flat against the outer faces of the side members, the lower portions of the flaps being free and resilient, and the bottom strip being arranged within the body with the opposite walls thereof inserted 90 between the side members and the free resilient portions of the terminal flaps, whereby the said side walls are frictionally engaged and clamped substantially throughout their entire length.

4. A collapsible or knockdown veneer box including a collapsible body consisting of a strip of veneer scored at the corners of the box and having overlapped terminals, and a bottom strip of veneer scored to form a bottom portion, upwardly extending side members, and terminal flaps which are folded downwardly and secured flat against the outer faces of the side members adjacent to the upper edges thereof, the lower portions of the flaps being free and resilient, and the said bottom strip being fitted within the body and the overlapped terminals thereof and the opposite wall of the said body being inserted between the free resilient portions 110 of the flaps and the side members, whereby the overlapped portions of the body strip and the opposite side wall are frictionally engaged and clamped substantially throughout their entire length.

5. A collapsible or knockdown veneer box including a collapsible body, and crossed bottom strips fitted within the body, each bottom strip being scored at intervals to form a bottom portion, upwardly extending supporting portions, and terminals flaps which are folded downwardly and stitched flat against the outer faces of the side mem- 125

bers, the lower portions of the said flaps being free and resilient and the opposite walls of the body being inserted between the resilient terminal portions of the flaps and the 5 side members, whereby the said walls are frictionally engaged and clamped substantially throughout their entire length.

In testimony, that I claim the foregoing as my own, I have hereto affixed my signature in the presence of two witnesses.

ORIN C. FENLASON.
